UNITED STATES PATENT OFFICE.

ESKIL BERG, OF SCHENECTADY, NEW YORK, ASSIGNOR TO GENERAL ELECTRIC COMPANY,
A CORPORATION OF NEW YORK.

CIGAR-LIGHTER.

No 896,348.

Specification of Letters Patent.

Patented Aug. 18, 1908.

Application filed April 26, 1907. Serial No. 370,357.

To all whom it may concern:

Be it known that I, ESKIL BERG, a citizen of the United States, residing at Schenectady, county of Schenectady, State of New York, have invented certain new and useful Improvements in Cigar-Lighters, of which the following is a specification.

This invention relates to electric cigar lighters and the like and has for its object the provision of a device of this character which will perform its functions in a quick and efficient manner and at the same time be thoroughly durable, cheap and reliable.

My invention relates most specifically to the type of cigar lighter described in the patent to Van Aller, No. 848,939. In this particular form of cigar lighter a resistance conductor is wound into coils and arranged so as to present a flat surface. Over this conductor a refractory shield is placed which will protect the conductor from blows and keep out foreign matter. Moreover a uniformly hot flat surface for contact with the cigar is provided.

In carrying out my invention I provide a shield of any desired material, which shield is perforated so as to permit a flow of air which must pass over the heated conductor and will thus save the resistance conductor and accomplish the lighting of a cigar in a more speedy and efficient manner.

In the drawings in which I have shown one embodiment of my invention, Figure 1 is a perspective view of a cigar lighter equipped with my invention; Fig. 2 is a plan view of a cigar lighter with the cover and shield removed; Fig. 3 is a plan view of the cover; and Fig. 4 is a perspective view of the shield.

Referring to the drawings 10 is an insulating base of any desired material, such as porcelain or the like, provided with screw thread and contacts adapting it for use in a lamp socket. The particular construction of this heating unit forms no part of my invention and is fully described in the Van Aller patent above referred to. The resistance coils 11 are mounted in the top of the base and arranged so as to present a flat surface. A cap or cover 12 is adapted to fit over the end of the base and is held in place by projections 13 fitting into grooves 14. The cover is cut away at its central portion so as to expose the shield 15, which is arranged between the resistance conductor and the cover and held in place thereby. This

shield is preferably formed in a thin disk and composed of some refractory material such as mica, lava or the like. In order to draw the heat away from the conductor, I provide the shield with perforations 16 which may be arranged in any desired manner. I have shown these perforations, which are seven in number, arranged substantially in the form of a circle, and it is found desirable that the perforations extend over an area substantially equal to that of the end of a cigar. Of course, the size of the perforated area is not an essential feature of my invention and may be varied at will.

By the use of my perforated shield it will be seen that as the cigar is lighted the hot air will be drawn through the perforations into the cigar thus lighting it quickly and thoroughly so that it is not essential that the disk reach a red heat before the cigar is lighted whereas without the perforations it is necessary that the shield comes up to the proper temperature.

It will, of course, be understood that various modifications of my invention will suggest themselves to those skilled in the art without departing from the spirit of my invention, the scope of which is set forth in the annexed claims.

What I claim as new and desire to secure by Letters Patent of the United States, is,—

1. A cigar lighter comprising an electric heating unit, and a shield having both an imperforate and a perforated portion arranged over and adjacent to said unit.

2. An electric cigar lighter comprising a base having a resistance conductor mounted thereon, and a shield having both an imperforate and a perforated portion arranged over said conductor and adjacent thereto.

3. An electric cigar lighter comprising a base having a resistance conductor mounted thereon, and a thin shield of refractory material having both an imperforate and a perforated portion arranged over said conductor and adjacent thereto.

4. An electric cigar lighter comprising a base having a resistance conductor mounted thereon, and a mica shield having both an imperforate and a perforated portion arranged over said conductor and adjacent thereto.

5. A cigar lighter comprising an electric heating unit, and a shield arranged over and adjacent to said unit, said shield having an

- imperforate area and a perforated area substantially the size of a cigar end.
6. An electric cigar lighter comprising an insulating base having a resistance conductor mounted thereon, and a thin imperforate shield of refractory material arranged over said conductor and having a perforated area substantially the size of a cigar end.
7. An electric cigar lighter comprising an insulating base having a resistance conductor mounted thereon so as to present a flat surface, and a shield arranged over said conductor and having a perforated area substantially the size of a cigar end.
8. An electric cigar lighter comprising an insulating base, a resistance conductor mounted thereon so as to present a flat surface, and an imperforate mica shield arranged over said conductor and adjacent thereto, said shield having a plurality of perforations extending over an area substantially the size of a cigar end.

In witness whereof, I have hereunto set my hand this 24th day of April, 1907.

ESKIL BERG.
